FOLDING BED FOR TRAILERS

Harold C. Brumbaugh, Portland, Oreg., assignor
of one-third to Max E. Krueger and one-third
to Herbert Heltzel, both of Portland, Oreg.

Application January 8, 1947, Serial No. 720,731

4 Claims. (Cl. 5—8)

1

My present invention relates to the provision of folding beds for human use in structures having but very little space therein, the invention being of particular utility in a folding trailer or the like.

I have illustrated the invention, and it is of particular utility, in connection with a folding trailer of the general type disclosed and claimed in co-pending application Serial No. 662,284, filed April 15, 1946, which became Patent No. 2,483,332 on September 27, 1949, but it is to be appreciated that the invention may be utilized in any dwelling structure such as a non-collapsible house trailer, a cabin or other type of house, a motor-boat, a sailboat, or other structures in which persons may desire to sleep.

An object of the present invention is to provide a folding bed so constructed and arranged that it may be collapsed upon itself and stowed away in a very small space, for example, beneath a work table or other structure such as a seat or the like so that the dwelling or the like may be utilized for normal daytime purposes and be converted into sleeping quarters during the night.

A further object of the present invention is to provide a folding bed which is hingedly supported in its location of use in such manner that the support thereof may comprise a work table or the like, which when lifted to a position of nonuse aids in lifting the bed to its position of use.

A further object of my present invention is to provide a lower bed in combination with an upper bed, the two beds forming a double-tier bunk arrangement, both beds being collapsible upon themselves and stowable within a small space such as beneath a work table, bench or the like.

A further object of my present invention is to provide a double-tier bed arrangement wherein the lower bed is foldable to a position of nonuse out of the way of the space traversed by the upper bed when it is being raised to a position of use.

The foregoing and other objects and advantages of the present invention will be more readily apparent from an inspection of the following specification taken in connection with the accompanying drawings wherein like numerals refer to like parts throughout.

In the drawings Fig. 1 is a vertical section through one end of a collapsible trailer such as disclosed in my co-pending application Serial No. 662,284, filed April 15, 1946, supra, having the present invention therein illustrated in its position of use;

Fig. 2 is a similar vertical section through the structure of my co-pending application wherein

2

the trailer is collapsed upon itself so as to present a small, compact structure capable of traveling at high speeds behind a towing vehicle, in which the present invention is illustrated in its stowed position;

Fig. 3 is a view in perspective showing the present invention with both beds in full line in their position of use, and the upper bed in dash lines in its stowed position;

Fig. 4 is a side elevational view of the present invention showing the upper bed in full outline in its stowed position and in dash lines in an intermediate position as well as in its position of use;

Fig. 5 is an end elevation taken from the right end of Fig. 4 illustrating the upper and lower beds in their stowed position in full outline and the upper and lower beds in their position of use in dash lines; and

Fig. 6 is an enlarged detail view taken substantially from the line 6—6 of Fig. 3.

Referring to Figs. 1 and 2 there is illustrated a collapsible trailer comprising a lower portion 10, an upper or roof portion 11, folding side walls 12 and a hinged end wall 13 adapted to be raised by mechanism 14. When the end walls and roof 11 are in raised position the side walls 12 will occupy vertical planes, and when the roof and walls are lowered the side walls 12 will collapse upon themselves as seen in Fig. 2. The mechanism 14 for raising and lowering the roof and walls of the trailer is incompletely illustrated herein as being unimportant to the present invention and details thereof may be ascertained from my co-pending application, identified above. It is to be appreciated that the structure could comprise a house trailer having its roof and walls permanently fixed in position, or that the structure could be any other form of dwelling, or a boat or the like.

Mounted against one wall of the trailer there is illustrated a work table comprising a table top 15 having a depending flange 16, the top being hinged to the side of the trailer at 17. As seen in Fig. 3 the top 15 may comprise the major portion of a work table including an end shelf 18, an opposed end shelf 19 having a sink or washbasin 20 therein, and a front wall 21 terminating in a stiffening rod 22 at its upper edge, all of these portions being permanently fixed in position. A hinge bar 25 is hinged to an intermediate portion of the lower surface of the top 15, there being one such bar at each end thereof, the lower ends thereof being attached to a U-shaped section of tubing 26 which is hingedly attached to the wall.

at 21, the section 26 forming a part of a lower bed frame. The ends of the arms of the section 26 are pivotally attached to arms of a U-shaped section of tubing 28, the section 28 forming the remainder of a substantially rectangular frame adapted to have body supporting means such as a wire or textile mesh 30 supported thereon so as to provide means to support a mattress or other bedding. The arms of the section 28 are preferably longer than the arms of the section 26 so that the section 28 may be folded against the wall, as seen in dash lines in Fig. 5, to remove the lower bed from a vertical plane above the position in which an upper bed is stowed. The lower bed is adapted to be raised from its position of non-use illustrated in full line in Figs. 2 and 5 to a position of use as illustrated in full line in Fig. 1 and in dash line in Fig. 5 wherein the bed frame occupies a substantially horizontal plane spaced above the floor of the structure in which it is located. The lower bed is adapted to be raised to its position of use by swinging the top 15 about its hinge 17 and latching the top to the wall 12 as by means of hooks 31 attached to the wall 12 and adapted to engage eyes 32 on the front surface of the portion 16, the hinge arms 25 thereby raising the arms of the section 26 to occupy a horizontal plane. The portion 28 may thereupon be leaned back toward the wall or may be left to occupy a horizontal plane, the joint thereof to the section 26 comprising any usual means for preventing breakage of the joint beyond the horizontal. The lower bed therefore may occupy a stowed position beneath the tabletop, a raised horizontal position of use, or a position in which the major portion thereof is folded back against the wall of the trailer.

An upper bed is adapted to be placed in stowed position as seen in Fig. 2 or its raised position of use as seen in Fig. 1. The upper bed comprises a frame including a U-shaped tube 35 forming one side and portions of the ends, an oppositely facing U-shaped tube 36 forming the other side and portions of the ends, and intermediate end sections 33 to which the extremities of tubes 35 and 36 are pivotally attached. The end sections 33 comprise U-shaped members which are braced by cross bars 37 providing convenient projections to support the pivot pins for the side members 35 and 36.

The lower ends of the U-shaped member 33 at the right end of the construction are pivotally attached to a horizontally disposed hinge tube 40 forming an end of a standard comprising spaced bars 41 and 42, the opposite ends of which comprise portions of a horizontally disposed hinge 43 mounted on a horizontal strut 44 suitably fastened beneath the fixed shelf 18. When the standard is in stowed position it depends from the strut 44 so that the hinge tube 40 lies closely adjacent the floor 45 of the trailer or other structure. The bars 41 and 42 are bent at point 46 so that the tube 40 is offset slightly from the hinge 43, thereby permitting the cross members 37 to occupy the position illustrated in Fig. 4. In order to raise this end of the upper bed after the lower bed has been folded back against the raised tabletop the bars 41 and 42 are swung upward around the hinge 43.

The opposite end of the upper bed is mounted upon an articulated standard including a pair of lower bars 50 pivotally attached at 51 to the floor 45. The upper ends thereof form portions of a hinge 52, from which extend a pair of upper bars 53, the opposite ends of which are pivotally at-

tached at 54 to an intermediate portion of the legs of the U-shaped member 33 forming a portion of the left end of the upper bed frame.

In order to raise the upper bed from its stowed position the left end thereof may be raised vertically and outwardly to a position above the fixed tabletop portion 19, the hinge tube 40 of the opposite end following as necessary to permit such movement. The bars 50 and 53 pass beyond a vertical plane until bars 53 abut against the edge of the top portion 19. The right-hand standard may thereupon be raised to a substantially vertical position, thus bringing the left-hand end of the bed to a substantially vertical point above its position of stowing.

When the standards have thus been raised to the position of use the sections 35 and 36 may be dropped to occupy a horizontal plane along with the cross bars 37. The frame may comprise means to prevent passage of the sections 35 and 36 beyond a horizontal plane but this is preferably assured by chains 55 and 56 extending from the tops of the U-shaped members 33 to the outer corners of the upper bed frame. A body supporting means such as a wire or fabric mesh 60 is spread upon the frame of the upper bed to provide means to support a mattress or the like. When the section 35 is in its horizontal position the upper bed may be braced against sideward movement by attaching the longitudinal portion thereof to the wall 12 as by means illustrated in Fig. 6. This means comprises a hinge having one leg 61 screwed to the wall and its opposite leg 62 formed into a U-shape adapted to embrace the tube. The upper end of the leg 61 is hooked to form means to retain a clamping ring 63 which is adapted to slip over the vertically disposed tip of the leg 62 to clamp the leg 62 against the wall. There are preferably two such retaining means at spaced points along the wall.

It will be noted, particularly from inspection of Fig. 4, that the extreme ends of the bars 41 and 42 pass beyond the vertical plane through the hinge 43 when the upper bed is raised, thus providing an over-center joint adapted to prevent the right standard from collapsing when weight is placed thereon. Also the hinge 52 at the left end of the upper bed passes beyond a vertical plane through the lower hinge 51 to provide an over-center means to prevent collapse of the left standard.

When the frame of the upper bed is folded upon itself in stowing position as seen in Figs. 2, 3 and 5 there is provided a U-shaped trough 55 within which a mattress and other bedding may be placed. When the lower bed is in stowed position the section 28 thereof is adapted to occupy a substantially horizontal plane as limited by engagement with the vertically disposed section 35 of the upper bed, there thus being provided a space between the lower bed and the tabletop 15 for the stowage of mattresses and other bedding.

It will be seen that I have provided a double bed construction adapted to occupy a very small space and retain therein the stowed mattresses and bedding, and which may be used either singly by raising only the lower bed or by raising the upper bed and folding the lower bed back against the wall, or both of which may be used at the same time. The upper bed may be left in its position of use and the lower bed restored to its stowed position by lowering the tabletop 15 after the upper bed has been raised, the tabletop 15 for this purpose being provided with a notch 65.

at one edge through which the bars 41 and 42 may pass and a notch 66 at its opposite edge through which the bars 50 may pass.

Having illustrated and described a preferred embodiment of my present invention it should be appreciated that modifications in detail and arrangement thereof may be readily achieved. All such modifications as come within the true spirit and scope of the appended claims are considered to be a part of my invention.

I claim:

1. A folding bed comprising a frame, a standard hingedly attached to one end of said frame, means hingedly supporting said standard at a point intermediate the plane occupied by the bed when in use and the floor of the structure in which it is located, an articulated standard hingedly attached at one end to the opposite end of said frame and to the floor of the structure at its other end, said articulated standard being capable of folding in either direction from its extended position, and means supported by said structure to prevent said articulated standard from folding more than a limited amount in one direction when the bed is in its position of use.

2. In a structure such as a trailer or the like, an upper folding bed comprising a frame, body-supporting means carried by said frame, a standard hingedly attached to one end of said frame, means hingedly supporting said standard at a point intermediate the plane occupied by the bed when in use and the floor of the structure, and an articulated standard hingedly attached at one end to the opposite end of said frame, and to the floor of the structure at its other end; in combination with a lower folding bed hingedly supported along one side within the structure to occupy a horizontal position below said upper bed when in its position of use, and movable to a position of non-use offset from the vertical plane of said standards, said lower bed extending between said standards when both beds are in their positions of use to prevent inward collapsing movement of said standards.

3. In a structure such as a trailer or the like an upper folding bed comprising a frame, a standard hingedly attached to one end of said frame, means hingedly supporting said standard at a point intermediate the plane occupied by the bed

when in use and the floor of the structure, and an articulated standard hingedly attached at one end to the opposite end of said frame, and to the floor of the structure at its other end; in combination with a lower folding bed hingedly supported along one side within the structure to occupy a position between said standards and below said upper bed when in use, and movable to a position of non-use over said upper bed when said upper bed and standards are folded into stowing relation.

4. In a structure such as a trailer or the like having a floor and an adjoining wall, an upper bed frame and a lower bed frame mounted in the space adjacent the junction between said floor and said wall so as to be in superimposed relation when in position for use, a pair of end standards pivotally connected to the ends of said upper bed frame and supporting said upper bed frame at a level above said lower bed frame when said standards are upright, said standards being articulated so as to be collapsible inwardly to permit lowering of said upper bed frame to a stowed position beneath said lower bed frame, and means connecting one side of said lower bed frame to said wall, and pivot means connecting the ends and opposite side of said lower bed frame to said one side whereby the major part of said lower bed frame may be swung to one side to permit raising or lowering of said upper bed frame, said lower bed frame when in its position of use after raising said upper bed frame has been accomplished extending between and preventing collapse of said standards.

HAROLD C. BRUMBAUGH.
